SELF-LOCKING CONTAINER

Marshall I. Williamson, New Haven, and Vincent R. Pantalone, Hamden, Conn., assignors to National Folding Box Company, New Haven, Conn., a corporation of New Jersey

Application August 19, 1943, Serial No. 499,198

5 Claims. (Cl. 229—35)

This invention relates to self-locking containers and is particularly directed to containers of the general tray and cover type formed of foldable sheet material, such as paper box board.

In accordance with the invention, the cover part and the tray part of such a container are so arranged as to automatically inter-lock when fitted together in normal telescopic relationship.

For this purpose, the cover part and the tray part each comprises complementary end or other side formations correlated to lock relative to one another when the cover part and the tray part are telescoped with respect to one another.

An effective complementary formation, say for each of the opposite ends of the cover part, is had by providing extensions of the side wall panels combined with an extension of the top wall panel, such extensions of the side wall panels, upon setting up the cover part, being respectively turned inwardly toward, and, in certain embodiments, partly overlapping, one another, the extension of the top wall panel being folded over upon and secured in fixed relation to the inwardly turned side extensions, thereby giving rise to notch-like or shouldered formations at the opposite ends of the cover part and inwardly thereof.

The complementary formation of the corresponding ends of the tray part may be similarly provided and set up, excepting that the two notch-like or shouldered end formations should be located outwardly of the tray.

Preferably, the two opposite top wall panel extensions of the cover part, and the corresponding extensions of the tray part, are each provided with one or more tabs projecting at the free edges thereof, and the side wall panel extensions of both cover part and tray part are provided either with mutually registering closed slots or mutually interlocking open-ended slots, or slots produced by infolding of the side wall panel extensions, for receiving such tab or tabs, to thus secure the notch-like or shouldered end formations in set up condition.

The notch-like or shouldered formations of the tray and cover part are so arranged that abutment edge portions are provided intermediate the depths of the respective end wall panels.

The respective cover and tray parts of any embodiment of the invention are preferably produced in unassembled flat blank status, the blanks thereof advantageously being identical, except for the obviously necessary lesser dimensions of the tray part relative to its associated cover part. The blanks may be assembled into set up condition as and when occasion warrants.

When the cover part and tray part are set up and telescopically inter-associated, the abutment edge portions of corresponding notch-like or shouldered formations thereof engage in mutually abutting relationship to automatically lock the two parts in their telescoped positions relative to each other.

In this condition, the end walls of the cover part present an altogether smooth and neat outward appearance, with the interlocked, notch-like or shouldered formations disposed inwardly thereof. Similarly, the end walls of the tray part are inwardly smooth and unbroken, the interlocked, notch-like or shouldered formations being disposed outwardly thereof. Thus, the walls of the container are smooth and unbroken wherever they come in contact with contents of the container as well as wherever they are visible to a purchaser or user of the packaged product.

Further features and objects of the invention will be more fully understood from the following detail description and the accompanying drawings, in which

Fig. 1 is an exploded view, in perspective, of a container or the like embodying the invention, a portion of a side of the cover part being broken away to expose otherwise hidden parts.

Fig. 2 is a detail sectional view on the line 2—2 of Fig. 1.

Fig. 3 is a detail top plan view of one end of the tray part of the container.

Fig. 4 is a detail sectional view on the line 4—4 of Fig. 3.

Fig. 5 is a detail perspective view of an end portion of the tray part, at a stage of setting up the indicated end of the same.

Fig. 6 illustrates the blank of the cover part of the preferred embodiment of the invention shown in Fig. 1, the blank of the tray part being similar except for slightly lesser dimensions.

Fig. 7 is an exploded view of interlocking end portions of the cover part and tray part, respectively, of another preferred embodiment of the invention.

Fig. 8 is a bottom view of the portion of the tray part shown in Fig. 7.

Fig. 9 illustrates one end fragment of the blank of the cover part of the embodiment of Figs. 7 and 8, the blank of the tray part being of similar formation, but slightly less in dimensions.

Fig. 10 is an exploded view, in perspective of another preferred embodiment of the invention.

Fig. 11 is a detail perspective view of an end

portion of the tray of Fig. 10, at a stage of setting up the indicated end of the tray.

Fig. 12 is a detail sectional view on line 12-12 of Fig. 10, where the cover part has been positioned over and is in locking relation with the tray part.

Fig. 13 illustrates the blank of the cover part of the embodiment of Figs. 10, 11 and 12, and likewise of the tray part assuming lesser dimensions as compared with the cover part.

Referring to the embodiment illustrated in Figs. 1 through 6, the cover part designated generally 20, is shown of rectangular configuration, comprising a top panel 21 and side panels 22, 22. The opposite ends of the cover part are shown as each provided with extensions 23, 23, respectively hingedly connected to the side panels 22, 22, and an extension 24 hingedly connected to the top panel 21. Each top extension 24 is scored as indicated at 25, giving rise to its flange portion 26; also each top extension is provided with a tab 27 projecting from the parallel free edges of the flange portion 26. Each side extension 23 is shown provided with a slot 28, referred to more fully hereinafter.

As appears from Figs. 1 and 2, the cover part is set up by "breaking" the indicated score lines, the setting up of each end of the cover part being had by infolding the extensions 23, 23, to project toward one another and to overlap at their terminal portions to effect register of their slots 28, then folding the top extension 24 and its flange portion 26 to embrace the extensions 23, 23 and inserting the tab 27 within the thus registered slots 28, 28.

The tray part of the embodiment shown in Figs. 1 through 5 may be constituted of panels, i. e. bottom and side panels which correspond generally to the top panel and the side panels of the cover part and are respectively designated by the same reference numbers bearing the suffix "a"; however, the parts constituting the opposite end portions of the tray part when set-up are disposed exteriorly thereof, whereas, as above set out, the end formations of the cover part are formed interiorly thereof.

As appears from Figs. 1, 2, 3 and 5, upon insertion of the tabs 27, 27, of the cover part and of the tabs 27a, 27a, of the tray part, notch-like or shouldered formations are brought about. The edge portions 29, 29 of each notch-like or shouldered formation of the cover part, and the edge portions 29a, 29a of each notch-like or shouldered portion of the tray part are mutually effective as locking elements. Such mutual locking effected by the respective sets of notch-like formations of the opposite ends of the cover part and the tray part is had by abutting engagement between the edge portions 29, 29, of the notch-like formations of the cover part relative to the edges 29a, 29a, of the tray part, and, to accomplish this, each terminal portion 26 of the cover part is preferably dimensioned slightly less than half the height of the end wall panel 24, whereby the edge portions 29, 29, of the notch-like formations of the cover part are located at a spacing from the edge of the open side of the cover part slightly greater than one-half the height of the cover part, and similarly with respect to the edge portions 29a, 29a and corresponding parts of the tray part.

It will be apparent from Fig. 1 that, upon telescoping the cover part over the tray part, the notch-like formations of the cover part ride over the notch-like formations of the tray part

until the locking edge portions 29, 29 thereof pass over and just beyond the locking edge portions 29a, 29a of the tray part. Thereupon, the notch-like formations of both tray and cover part snap or flex into locked relationship.

It will be observed that each notch-like formation possesses a relatively bulged portion, caused by a tab 27 or 27a being inserted within its registered slots 28 or 28a, respectively. Desirably, the dimension of the tray part in the direction between its notch-like formations is but slightly less than the dimension of the cover part between its corresponding end formations, whereby upon telescoping the cover part upon the tray part such flaring of the locking flange edges results in a sliding frictional relationship between the respective end formations. Upon passing and clearing of the bulged portions of the respective notch formations, the resiliency of the flexible sheet material of the cover part and of the tray part causes a snap movement in effecting the mutually locked relationship, see Fig. 4.

To disengage the cover part from the tray part, a suitable instrument, preferably flat, such as the blade of a knife, is inserted between the respective end formations of the tray part and of the associated end formations of the cover part and upon application of force applied to either or both of the cover part and the tray part, the cover part is separated and released from the tray part.

The embodiment shown in Figs. 7, 8 and 9 corresponds generally to that shown in Figs. 1 through 6. However, the embodiment of Figs.

7, 8 and 9 comprises notch-like end formations respectively interiorly of the cover part formed of extensions 30, 30, at each end of the cover part hingedly connected respectively with the opposite side panels, 31, 31; each extension 30 is provided with an open slot such as shown at 32 at the indicated edge. Such notch formation also includes an extension 33 hingedly connected to the top panel 34, having a terminal portion 35 which is provided with two tabs 36, 36. The free edge portions of the terminal portion 35 are indicated 37. In this embodiment, as appears from the upper part of Fig. 7 illustrating an end portion of the cover part 20, upon inter-folding the extensions 30, 30, and folding thereover the top extension 33, the tabs 36, 36, are respectively insertable in the thus registered set of dual slots 32, 32.

The tray part of the embodiment of Figs. 7, 8 and 9 is shown similarly constituted, the constituent elements of the tray part including its exterior notch-like end formations being designated by corresponding reference numbers with the suffix "a."

It will be noted in the embodiment of Figs. 7 and 8, that three mutually spaced notch edge portions 37, 37, 37 are presented in the respective end formations of the cover part, located interiorly of the cover, and a correspondingly three, therewith abutting notch edge portions 37a, 37a, 37a are presented exteriorly of the tray part at its opposite end portions.

In the embodiments shown in Figs. 10 through 13, the cover part denoted generally 20 is provided at each end with extensions 40, hingedly connected to its side panels 22, 22; and its top panel 21 is provided with an extension denoted generally 41. Further, such side extension is inset, indicated at 42, relative to its side panel 22, for purposes set forth more fully hereinafter; each side extension is also scored diagonally as

shown at 45. The top extension 41 and the respective side extensions 40, 40, at each end of the cover part are hingedly related by score lines 44, 44.

The top extension 41, at each end of the cover part, is scored at line 45 (in alignment with the extreme edges of the side extensions 40, 40), giving rise to the terminal portion 46, which is preferably tapered, as shown, at its side edges. Each terminal portion 46 has a tab 47 hingedly connected thereto by score line 48, and each tab 47 is provided intermediately with a series of mutually parallel crease lines 49 (three shown).

The tray part of the embodiment of Figs. 10 through 13, comprises parts corresponding to those just described with respect to the cover part, and are correspondingly designated with the suffix "a." The tray parts, however, are of slightly lesser dimensions to afford reception thereover of the cover part by a close fit.

The cover part and the tray part of the embodiment of Figs. 10 through 13 are set up in a manner similar to that of the corresponding parts of the previously described embodiments, and in like manner give rise to mutually interlocking notch formations at each end interiorly of the cover part and exteriorly of the tray part.

Taking the tray part of this embodiment as an illustration, it is set up by "breaking" the indicated score lines hingedly connecting the side panels 22a, 22a, with the bottom panel 21a. This movement of setting up the side panels 22a, 22a, is accompanied by upward movement of the bottom extension 41a, as indicated in Fig. 11, with self-infolding of the respective side extensions 40a, 40a, each upon itself, afforded by its diagonal score line 42a and exteriorly of the contour of the tray part. Each terminal portion 46a is then outwardly folded over its associated infolded side extensions 40a, 40a and locked in notch formation by tucking in its tab 47 (facilitated by its mutually parallel crease lines 48), to embrace and retain the respective folded side extensions 40a, 40a. The set up tray part 20a is shown in the lower portion of Fig. 10. It will be observed that the edge located at 48a, and formed by the crease 48a upon inserting the tab 47a into position, is disposed at a spacing from the top edge of the open upper side of the tray part less than one-half of the height of tray part.

The cover part 20 is set up in the manner similar to that of the tray part 20a, the set up cover part being shown in the upper portion of Fig. 10. The edge 48 of the cover part is thus disposed at a spacing from the top panel 21 less than one-half of the height of the cover part.

As is readily deducible from Fig. 10, and as is shown specifically in Fig. 12 with respect to one end of the assembled and mutually locked cover part 20 and of the tray part 20a, the respective notch formations of the cover part and of the tray part pass one another when the cover part is telescoped upon the tray part until the edge 48 of the cover part clears the edge 48a of the tray part, whereupon the resiliency of the two notch formations comes into operation, whereafter the edge 48 of the notch formation of the cover part is locked relative to and by the edge 48a of the notch formation of the tray part.

It is noted that the insets indicated at 42 of each side extension relative to its associated side panel and top extension of the cover part, similarly with respect to the corresponding insets of the side extensions of the tray part, compensate for the thickness of the top or bottom exten-

sion when set up, as above described, to present a flush edge at the open side of the cover part and likewise with regard to the tray part.

This last described embodiment of the invention has the important advantage of water-tight corners.

Whereas the invention is here described with respect to certain preferred specific embodiments thereof, it should be understood that various changes can be made in such specific embodiments and various other embodiments can be produced by those skilled in the art without departing from the spirit and generic purview of the invention as set forth herein and in the claims 15 which here follow.

I claim:

1. In a self-locking container, the combination of a tray part and a therewith outwardly telescoping cover part, each said part comprising 20 yieldable sheet material, the cover part being closely dimensioned with respect to the tray part; the tray part having exteriorly of its opposite end panels and the cover part having interiorly of its opposite end panels juxtaposed mutually locking formations, each end locking formation comprising an extension of said end panel and extensions of the therewith associated side panels, the side panel extensions being folded to overlap one another intermediately of the end panel and 25 the end panel extension being folded to overlap the overlapped portions of the side panel extensions, thereby giving rise to bulging intermediate the end panel, the end panel extension terminating in an intermediately disposed tab and therefrom 30 oppositely extending mutually parallel free edges, the side panel extensions providing an opening for the reception of the tab and for maintaining such intermediate bulging of the lock formation, the parallel free edges of the juxtaposed 35 end locking formations of the cover extending below the parallel free edges of the end locking formations of the tray, whereby upon telescoping the cover part over the tray part the intermediate bulging formations and the close dimensioning of the container parts effect mutual abutting engagement between the respective associated free edges of the locking formations to thereby 40 lock the cover part relative to the tray part.

2. In a self-locking container, the combination of a tray part and a therewith outwardly telescoping cover part, each said part comprising yieldable sheet material, the cover part being closely dimensioned with respect to the tray part; the tray part having exteriorly of its opposite end panels and the cover part having interiorly of its opposite end panels juxtaposed mutually locking formations, each end locking formation comprising an extension of such end panel and extensions of the therewith associated side panels, the side panel extensions being folded to overlap one another centrally of the end panel and the end panel extension being folded to overlap the overlapped portions of the side panel extensions, thereby giving rise to bulging intermediate of the end panel, the end panel extension terminating in a centrally disposed tab and therefrom oppositely extending mutually parallel free edges, the side panel extensions providing an opening for the reception of the tab and for maintaining such central bulging of the lock formation, the parallel free edges of the juxtaposed end locking formations of the cover extending below the parallel free edges of the end locking formations of the tray, whereby upon telescoping the cover part

over the tray part the central bulging formations and the close dimensioning of its container parts effect mutual abutting engagement between the respective associated free edges of the locking formations to thereby lock the cover part relative to the tray part.

3. In a self-locking container, the combination of a tray part and a therewith outwardly telescoping cover part, each said part comprising yieldable sheet material, the cover part being closely dimensioned with respect to the tray part; the tray part having exteriorly of its opposite end panels and the cover part having interiorly of its opposite end panels juxtaposed mutually locking formations, each end locking formation comprising an extension of said end panel and extensions of the therewith associated side panels, the side panel extensions being folded to overlap one another intermediately of the end panel and the end panel extension being folded to overlap the overlapped portions of the side extensions, thereby giving rise to bulging intermediate the end panel, the end panel extension terminating in an intermediately disposed tab and therefrom oppositely extending mutually parallel free edges, the side panel extensions being provided with mutually registering slots for the reception of the tab and for maintaining such intermediate bulging of the lock formation, the parallel free edges of the juxtaposed end locking formations of the cover extending below the parallel free edges of the end locking formations of the tray, whereby upon telescoping the cover part over the tray part the central bulging formations and the close dimensioning of its container parts effect mutual abutting engagement between the respective associated free edges of the locking formations to thereby lock the cover part relative to the tray part.

4. In a self-locking container, the combination of a tray part and a therewith outwardly telescoping cover part, each said part comprising yieldable sheet material, the cover part being closely dimensioned with respect to the tray part; the tray part having exteriorly of its opposite end panels and the cover part having interiorly of its opposite end panels juxtaposed mutually locking formations, each end locking formation comprising an extension of such end panel and extensions of the therewith associated side panels, the side panel extensions being folded to overlap one another centrally of the end panel and the end panel extension being folded to overlap the overlapped

portions of the side panel extensions, thereby giving rise to bulging intermediate of the end panel, the end panel extension terminating in a centrally disposed tab and therefrom oppositely extending mutually parallel free edges, the side panel extensions being provided with mutually registering slots for the reception of the tab and for maintaining such central bulging of the lock formation, the parallel free edges of the juxtaposed end locking formations of the cover extending below the parallel free edges of the end locking formations of the tray, whereby upon telescoping the cover part over the tray part the central bulging formations and the close dimensioning of its container parts effect mutual abutting engagement between the respective associated free edges of the locking formations to thereby lock the cover part relative to the tray part.

5. In a self-locking container, the combination of a tray part and a therewith outwardly telescoping cover part, each said part comprising yieldable sheet material, the cover part being closely dimensioned with respect to the tray part; the tray part having exteriorly of its opposite end panels and the cover part having interiorly of its opposite end panels juxtaposed mutually locking formations, each end locking formation comprising an extension at the outward free edge of said end panel and extensions of the therewith associated side panels, the side panel extensions being folded to overlap one another intermediately of the end panel and the end panel extension being folded to overlap the overlapped portions of the side panel extensions, thereby giving rise to bulging intermediate the end panel, the end panel extension terminating in an intermediately disposed tab and therefrom oppositely extending mutually parallel free edges, the side panel extensions providing an opening for the reception of the tab and for maintaining such intermediate bulging of the lock formation, the parallel free edges of the juxtaposed end locking formations of the cover extending below the parallel free edges of the end locking formations of the tray, whereby upon telescoping the cover part over the tray part the intermediate bulging formations and the close dimensioning of the container parts effect mutual abutting engagement between the respective associated free edges of the locking formations to thereby lock the cover part relative to the tray part.

MARSHALL I. WILLIAMSON.
VINCENT R. PANTALONE.
